GUN CONTROL MECHANISM

Hans Ernst and Bernard Sassen, Cincinnati, Ohio,
assignors, by mesne assignments, to the United
States of America as represented by the Secre-
tary of the Navy

Application November 22, 1937, Serial No. 175,830

8 Claims. (Cl. 89—41)

1

This invention relates to motion transmitting or signaling systems and more particularly to the type wherein a follower is caused to move in synchronism with a transmitter or director.

One of the objects of this invention is to provide an improved system which is highly sensitive to any movement of the transmitter; which is positive in operation; and which is capable of developing the necessary torque for effecting movement of a receiver and also maintaining the same in synchronous relation with the transmitter.

Another object of this invention is to develop a system of the character mentioned which although sensitive to a high degree, may be of rugged construction, thereby eliminating delicate parts susceptible of easy breakage, or sensitive to shocks causing maladjustment thereof.

A further object of the invention is to provide a system as aforesaid in which hydraulic means may be utilized as the motion conveying or signaling medium.

An additional object of this invention is to provide a system of the character mentioned which may be compounded in such a manner that movement in a plurality of planes may be placed under the control of a single element, thereby providing a system which is suitable for fire control purposes of military forces and especially adapted for control of anti-aircraft defense weapons.

Other objects and advantages of the present invention should be readily apparent by reference to the following specification, considered in conjunction with the accompanying drawings illustrative of one embodiment thereof, but it will be understood that any modifications may be made in the specific structural details within the scope of the appended claims without departing from or exceeding the spirit of the invention.

Referring to the drawings in which like reference numerals indicate like or similar parts:

Figure 17 is a diagram of the hydraulic resistances.

Figure 18 is a diagrammatic view showing the 25 relation between the change of resistance in the transmitter elements relative to the change of resistance in the receiver elements.

This invention in its broad aspects, contemplates a signaling system for the transmission of motion impulse signals from a transmitter to a receiver in a definite and positive manner, and so that one will always be in synchronism with the other, whether at rest or in motion. In the attainment of absolute synchronism, a constantly acting force must be ever present so that even after a signal has been transmitted, the interconnected parts will be held and maintained in their new positions thereby preventing inadvertent or accidental movement of the receiver out of synchronism with its transmitter or director. More specifically, this invention contemplates a signaling system in which an hydraulic medium is utilized for transmitting signals such as motion impulses, and which is so contrived as to provide a first group of properly related pressural control elements in the transmitter which act through individual hydraulic lanes to alter or unbalance the respective pressures on an equal group of receiver actuators arranged to be effective as a couple to cause movement of an ultimate receiver element, which movement will continue until the actuators themselves by their own movement cause reequalization of the pressures acting upon them, and thereby equilibrium between the parts which not only stops the receiver element but holds it in a given position.

tion. Accurate positioning is obtained because each increment of movement of the director causes a definite pressure differential on the actuators which will not be eliminated until the receiver actuators have moved through that same increment.

Having effected a new position, the fluid pressure still acts but in an equalized manner so that even if the receiver actuators are inadvertently or accidentally disturbed, the fluid pressure will again bring them into synchronized relation with the respective control elements. Such a system is thus admirably adapted for controlling, for instance, the azimuth or elevation of a gun from a remote fire control station and more particularly for controlling the position of anti-aircraft defense weapons. On account of the rapid movement of aircraft, it is extremely difficult to follow their movements with the ordinary gun sights because alignment of the sights with the target means movement of the gun, which is so-unwieldly as to prevent easy and fast manual movement thereof. It is therefore desirable to use independent, easy and quickly movable sighting apparatus for this purpose. It is obvious that the movements of this apparatus must be immediately transmitted to the gun so that it will always be in a position to fire as soon as the target is properly located. In such a combination the sighting apparatus can be considered as the transmitter; and the gun as a receiver thus presenting an ideal condition for the application of this invention and it will therefore be described in connection with an anti-aircraft defense weapon for control thereof.

The relative position of such a gun and its control mechanism may be the same as that shown in Figure 1 in which the reference numeral 10 indicates generally the gun, while the reference numeral 11 indicates in a general manner the control for the gun. Since aircraft in general are capable of three directional movement as distinguished from the two directional movement of ordinary land or naval forces, it is necessary that the weapons used to combat aerial forces have a greater range of adjustment than the ordinary land and naval weapons; and for this reason, the gun barrel 11 is carried or mounted on a support 12 which has limited angular movement about a pivot 13 and in the plane of the upper surface 14 of a sub-support 15. This sub-support is mounted for movement about a pivot 16 for elevational adjustment of the gun, the pivot being carried by a column or standard 17 which itself is angularly adjustable in a horizontal plane about a pivot 18, the weight of the standard being transmitted through anti-friction bearings to a base member 20. It will thus be seen that the gun may be adjusted in a horizontal plane about the pivot 18; in a vertical plane about the pivot 16, and in an inclined plane about the pivot 13.

The sighting apparatus must be capable of corresponding movement in these various planes in order to properly control the gun by merely sighting the target, and for this reason the director or sighting arm 21, carrying sights 22, at opposite ends thereof, is mounted for movement about a pivot 23, carried by a sub-support 24, mounted for angular movement in a vertical plane about the pivot 25. The pivot 25 is carried by a vertical standard 26 which is mounted for rotation about a pivot 27, its weight being transmitted to the base 28 through anti-friction bearings 29. The director arm 21 may be moved through means of the hand grasp 30, secured to one end thereof,

by the gunner or other operator, in a vertical plane, or for limited movement in any inclined plane about the pivot 23, or for complete movement through a circle about the pivot 27. Since the movement about the pivot 27 is effected by a separate hand grasp 31 integral with the member 26, the movement about the pivot 23 is provided so that small adjusting movements may be made more quickly than if dependence was placed upon the control 31.

Mechanism has been provided whereby any movement of the sighting apparatus will be immediately communicated to the corresponding movable elements of the gun so that the axis of the gun will always be in synchronism with the axis passing through the sights 22. The sighting apparatus therefore constitutes a form of transmitter which is utilized to signal the movements to be made in the gun, the system contemplated by this invention effecting the gun movements automatically, and simultaneously with the movement of the sighting apparatus.

A separate transmitter, such as shown at 32 in Figure 9, is operatively connected with each movable element so that the movement in the respective planes is transmitted by individual transmitters. Similarly, each of the movable parts of the gun support is provided with an individual receiver which is of the same form as the transmitter 32 shown in Figure 9, and this receiver is coupled for control of an hydraulic motive power unit for translating the signal received into power movement of the gun. It should thus be obvious that the three possible planes of movement of the sighting apparatus have three separate transmitters which are connected to individual receivers in the gun, thereby constituting in effect three separate and distinct communication or signaling systems. Since all of the systems are the same, only one will be described herein; but it is to be remembered that even although they function as separate entities they still may be provided with fluid pressure from a common source.

As shown in Figures 9, 10 and 11, the transmitter comprises a housing 33 containing a cylinder block 34, in which is formed a plurality of cylinders 35, 36, 37 and 38. Piston members 39, 40, 41 and 42 are mounted in the respective cylinders 35, 36, 37 and 38 for movement toward and from a common center member 43. Each piston has an anti-friction roller 44 journaled in the outer end thereof for cooperation with the inner contoured surface 45 of the manually rotatable member 46. The cylinder block 34, as more particularly shown in Figure 11, is inter-drilled to provide a passage 47, to which the pressure channel 48 is connected when the device is used as a transmitter. When the device is used as a receiver a reservoir return line is connected to this passage. The passage 47 is connected by four axially extending holes 49, 50, 51 and 52 to separate angularly shaped passages 53, 54, 55 and 56. These passages terminate in ports intersecting the respective cylinders, there being two ports on opposite sides of each cylinder so that the pressure serves to balance the pistons in the cylinders and prevent binding thereof. Each piston has a pair of grooves 57 formed on opposite sides thereof. Also, the portions of the periphery of the piston between the boundaries of the grooves 57 are reduced in diameter by a few thousandths of an inch as shown in 58 in Figure 11. A diametrical hole 59 in the piston interconnects the grooves 57 with an axial hole 60 drilled in one end of each

piston, these axial holes terminating at the space 61 existing at the inner end of each cylinder. The spaces 61 communicate with separate passages 62, 63, 64 and 65 formed in the center portion of the cylinder block and each in turn is connected with a separate pipe extending to the receiver. When the device shown in Figures 10 and 11, is utilized as a transmitter, fluid pressure may be supplied, as by the channel 48, to the cylinder ports, through which it then passes to and through the narrow spaces 66, 67, 68 and 69, which constitute hydraulic resistances, to the intersecting passages 59 and 60, and from there through the spaces 61 to the respective channels 62, 63, 64 and 65. These hydraulic resistances cause a drop in pressure between the incoming fluid in channel 48 and the outgoing fluid in channels 62, 63, 64 and 65. Also, the hydraulic resistances will cause a different drop in pressure for each piston, depending upon the axial position thereof in its cylinder, it being apparent that when the piston 39, for instance, is at the limit of its outward stroke, the resistance will be at a maximum; while when the piston, such as 41, is at the end of its inward stroke the resistance will be at a predetermined minimum. Since there will always be a substantial pressure in the spaces 61, this pressure will act continuously to force the various pistons outward, which outward movement will be limited by the member 46, and by the shape of the contour which happens to be opposite the respective pistons.

The inner surface of the member 46 is provided with an uneven number of hyperbolic shaped surfaces 70, each of which has the same contour and which are so formed that upon movement of the member 46 through an arc indicated by the reference numeral 71, the piston will be moved inward through a complete stroke causing the hydraulic resistance to vary at a substantially uniform rate from maximum to minimum, or from minimum to maximum depending upon the direction of rotation of the cam 46. Upon unidirectional movement of the member 46, one half of the surface 70 may be considered as a piston advancing portion and the other half as a piston retracting portion.

When the device shown in Figures 10 and 11 is utilized as a receiver, the direction of flow through it will be reversed, the fluid entering through channels 62, 63, 64 and 65 to act on the ends of the pistons and cause clockwise or counter-clockwise rotation of the member 46 and discharging through the hydraulic resistances in the various pistons to a return channel, which would be substituted for the channel 48.

It will thus be seen that the system in its elementary form comprises a source of fluid pressure which is connected to a plurality of parallel resistances which are simultaneously variable, as by manual rotation of the member 46, in predetermined relation to one another, and a serially arranged equal number of resistances, which are automatically variable in the same phase relation so that definite pressures are created between the respective pairs of serial resistances, such as in the channels 62, 63, 64 and 65 and that the pressures in these channels may be varied by changing the resistance at either side thereof.

In order to more clearly understand this relationship, a simple diagram has been shown in Figure 17 in which the pressure supply line is represented by the numeral 72; the hydraulic

resistances associated with pistons 39, 40, 41 and 42 by the respective resistance coils 73, 74, 75 and 76 while the corresponding resistances in the receiver member are diagrammatically illustrated by the coils 77, 78, 79 and 80, the respective pairs of resistances being interconnected by channels 62', 63', 64' and 65' corresponding to channels 62, 63, 64 and 65 in Figure 10. The fluid escaping from the resistances 77 to 80 inclusive may be connected in a common return line 81 and returned to a common reservoir. Although the channel 72 has been indicated as a pressure channel and the channel 81 as a return line, the functions of these could be reversed without changing the effect or operation of this device.

Although four lines have been shown in Figure 17, a minimum of three parallel lines could be used; but since such an arrangement would not produce uniform turning torque throughout the 360 degrees of movement of the device, it is preferable to use a larger number although the actual number used does not depart from the principles of this invention.

By using four channels, it is possible to arrange the pistons in opposing pairs, or in other words, in couples, so that while one pair is passing a dead center, the other pair is active and capable of causing reverse rotation of the receiver.

It is a well-known hydraulic principle that the pressure P in a channel is a function of the quantity Q flowing through the channel, and the resistance R in the remainder of the channel between the point where the pressure is taken and the outlet; and this relationship may be expressed as

$$P=QR$$

In Figure 17 a portion of the various parallel branch lines indicated as 53', 54', 55' and 56' correspond respectively to channels 53, 54, 55 and 56 in Figure 10. The pressure in each of these lines will be the same as the pressure in the main supply line 72 and therefore in accordance with the preceding equation, a separate equation may be written for each parallel branch line. In these equations Q^1 , Q^2 , Q^3 , and Q^4 represents the quantity of flow in the respective branch lines.

- 50 (1) $P=Q^1(73+77)$
- (2) $P=Q^2(74+78)$
- (3) $P=Q^3(75+79)$
- (4) $P=Q^4(76+80)$

55 Also if P^1 , P^2 , P^3 , and P^4 represent the pressure in the respective channels 62', 63', 64' and 65' we may write the following equations:

- 60 (5) $P^1=Q^1(77)$
- (6) $P^2=Q^2(78)$
- (7) $P^3=Q^3(79)$
- (8) $P^4=Q^4(80)$

65 Dividing Equations 5, 6, 7 and 8 by Equations 1, 2, 3 and 4 respectively, we have in simplified form:

- (9) $P^1=P\left(\frac{77}{73+77}\right)$
- (10) $P^2=P\left(\frac{78}{74+78}\right)$
- (11) $P^3=P\left(\frac{79}{75+79}\right)$

$$(12) \quad P^4 = P \left(\frac{80}{76+80} \right)$$

If now resistance 73 is equal to resistance 77; 74 equal to 78; 75 equal to 79; and 76 equal to 80, it will be found that

$$P^1 = \frac{P}{2}$$

$$P^2 = \frac{P}{2}$$

$$P^3 = \frac{P}{2}$$

$$P^4 = \frac{P}{2}$$

It will therefore be apparent that the respective pressures P^1, P^2, P^3, P^4 are each equal to one-half of the pressure in the main line 72. In other words if the resistance to flow "in" is equal to the resistance to flow "out" of a given channel the pressure intermediate the resistances is always equal to one-half of the supply pressure. It should be remembered, however, that this does not mean that because resistance 73 is equal to resistance 77, for instance, that the resistance 73 must be equal to the resistance 74 or resistance 75, or the resistance 76. Each one of these four resistances may have different values but so long as the remaining serial resistance is equal to the first resistance, the intermediate pressure will be one-half of the supply pressure. It is thus possible to have the piston 39 at the end of its outward stroke, and the piston 41 at the end of its inward stroke, one presenting a maximum of resistance and the other a minimum resistance, and still have the pressure at 62 and 64 in Figure 10 equal to one another. Similarly, the pressure at 63 and 65 may be equal to one another, and since all four pressures are equal, no movement will result in the rotatable member 46.

The change in resistance caused by any piston may be plotted against the length of piston stroke as shown by the graph 82 in Figure 18 in which the distance X represents the length of piston stroke and the distance Y represents the change in resistance from any predetermined minimum to any predetermined maximum. The orifices or ports and the surfaces 45 are so shaped that this change in resistance is substantially uniform throughout the length of piston stroke. Also, since the length of piston stroke corresponds to the movement of the member 46 through the arc 71 the length of piston stroke might also be considered the length of angular movement of the member 46 through the arc 71. Therefore, a reference line 83 has been drawn in Figure 18 and the graphs 84, 85 and 86 positioned relative to this reference line in accordance with the phase relationship of pistons 41, 40 and 42 respectively relative to the piston 39. In other words the hydraulic resistance of piston 39 is at a maximum, as indicated by the point 87 in graph 82, the hydraulic resistance of piston 41 is at a minimum indicated by the point 88 in graph 84, the resistance of piston 40 is substantially intermediate the minimum and maximum resistance possible as indicated by the point 89 in graph 85; and similarly the resistance of the piston 42 is the same as piston 40 as indicated by the point 90 in graph 86. If the reference line 83 is considered to be the member 46, it will be seen that if this line is moved in the

direction of the arrow 91 corresponding to clockwise movement of the member 46 such as to the position indicated by the dash and dot line 92 that the resistance of piston 39 will decrease from the point 87 to the point 93; the resistance of piston 41 will increase to the point 94; the resistance of piston 40 will decrease to the point 95, and the resistance of piston 42 will increase to the point 96. Conversely, if the line 83 is moved in the direction of arrow 91, corresponding to the counter-clockwise direction of member 46, the hydraulic resistance of the various pistons will change in accordance with the graphs 98, 99, 100 and 101. A second set of graphs 102, 103, 104 and 105 have been drawn to represent the corresponding hydraulic resistance in the receiver member. Since the transmitter and receiver should always be in the same relative position, these graphs will be in the same phase relationship to the reference line 106 as the preceding set of graphs whereby the resistance as indicated by the points 107, 108, 109 and 110 will be equal to the preceding resistances and should change in the same relationship. The respective pairs of resistances have been connected by channels 62', 63', 64' and 65' in accordance with Figure 17. It will now be seen that when the resistance "in" to line 62' is equal to the resistance "out" of it, that the pressure in this line will be equal to one-half the main pressure, and since the same is true with channel 63' it will be seen that the pressure on opposite sides of the intermediate piston 111 will be the same and no movement will result. Also, the pressure on opposite sides of the piston 112 intermediate lines 64' and 65' will be the same and no movement will result.

If now the member 46 is rotated in a clockwise direction indicated by the arrow 91, there will be a momentary unbalancing of the pressure in the various channels due to the fact that the resistance "in" in all of these channels is now different from the resistance "out" of them. In other words, the pressure P^1 in channel 62' has decreased which will be evident from equation 9, because the resistance 77 will now be less and therefore P^1 will be a smaller fraction of the pressure P than it was formerly. Similarly the pressure at P^2 will be increased due to the increase in the value of the resistance 78. Since the pressure in channel 63' is now greater than the pressure in channel 62', there will be an unbalancing of the forces acting on the piston 111 and in such a direction as to cause clockwise movement. Also, the pressure at P^3 in line 64' will be less than the pressure in channel 65' which again will act on the intermediate piston 112 to cause clockwise movement. This clockwise movement is equivalent to movement of the reference line 106 to its dash and dot position indicated by its reference numeral 106'. When this position is reached, it will be seen that the resistances will now be equal to the incoming resistances and the opposing pressures and the pistons 111 and 112 will again equalize, restraining any further movement and simultaneously maintaining the parts in a fixed position.

The pressure on opposite sides of the pistons 111 and 112 diagrammatically represent the opposing pressures on the pair of pistons 39, 41 and on the pair of pistons 42 and 40. It should now be clear that when the transmitter member 46 is rotated either clockwise or counterclockwise, that differential pressures will now be set up in channels 62, 63, 64 and 65 which will cause the

pistons in the receiver member to assume the same position as those in the transmitter, or in other words be in synchronous relation therewith.

One form of construction by which the transmitter is interconnected with the receiver is shown in Figures 2 and 3, the transmitter being shown in Figure 3 and the receiver or gun being shown in Figure 2. In Figure 3 the hydraulic transmitter 113 is fixed with the column 11 and provided with a bevel gear 114 on one end of a shaft 115 which is directly connected to the cam member 46. A large bevel gear 116 which is in the ratio of 6 to 1 to the bevel gear 114 meshes therewith whereby one rotation of the gear 116 will effect six rotations of the cam 46. A second bevel gear 117 is integral with gear 116 and both are mounted for free rotation on the shaft 118 carried by the column 11. The gear 117 meshes with the bevel gear 119 keyed to the end of pivot pin 23 which is mounted for free rotation in the support 24 but is keyed with the support 21 which carries the sights 22.

The hydraulic transmitter 113 is connected by four individual channels 120, 121, 122 and 123 to the hydraulic receiver member 124 which, as shown in Figure 6, is mounted in one end of a housing 125. The receiver member controls a motive power unit indicated generally by the reference numeral 126 and which is coupled to the receiver in the manner of a servomotor. The output of this motive power unit is transmitted to shaft 127 having a worm gear 128 secured to the end thereof in mesh with a worm wheel 129 mounted for free rotation on the shaft 130. A bevel gear 131 is formed integral with the worm wheel and meshes with a similar bevel gear 132 which is keyed to one end of shaft 133, this shaft being mounted for free rotation on the sub-support 15 but keyed at its upper end to the gun support 11. It should now be evident that when the sight support 21 is rotated in the plane of the upper surface of the sub-support 24 regardless of the angle of this plane, that the hydraulic transmitter will be rotated through the intermediate gearing to a definite position thereby disturbing the existing pressures in channels 120 to 123 inclusive which will cause a corresponding movement from the receiver 124 until those pressures have been equalized again, and when this equalization occurs the receiver will be in the same relative position as the transmitter. This rotation of the receiver will cause a predetermined movement of the servomotor 126 and thereby rotation of the gun support 11 to a position parallel to the position of the sighting support 21.

The sub-support 24 has a bevel gear 134 secured thereto which meshes in six to one ratio with a bevel gear 135 secured to the end of a shaft 136 of a second hydraulic transmitter 137. This transmitter is connected by lines 138, 139, 140 and 141 to a receiver 142 which operates in turn a motive power unit 143 connected through worm 144 and worm wheel 145 to the sub-support 15.

The motive power unit 126 is coupled to the receiver in a ratio of one to six so that one rotation of the receiver 124 will effect six revolutions of the shaft 127. Also the ratio of the worm 128 to the worm wheel 129 is 36 to 1 so that it will take 36 revolutions of the worm to effect one rotation of the worm wheel. These two trains thus make it possible for any movement of the gun sights about the pivot 23 or about the pivot 118

to be immediately transmitted to the gun support 11 and correspondingly position it about the pivots 13 and 130 parallel to the axis of the sights carried by the support 21. The construction shown in Figures 2 and 3 requires a flexible hydraulic connection between the transmitter and receiver due to the fact that the transmitters are carried by the support 10 which is also rotatable about the pivot 18 while the receiving elements are carried by the support 11 which is rotatable about the pivot 27.

The details of this flexible connection are shown in Figures 7 and 8 and comprise a tapered plug 146 carried by the base 20 rotatably fitting in a tapered bore formed in the housing 147 which is carried by the standard 10 and rotatable therewith. This plug has four annular grooves 120', 121', 122' and 123' to which the channels 120 to 123 inclusive are connected, and a second group of four annular grooves 138', 139', 140' and 141' to which the channels 138 to 141 inclusive are connected. Each one of these connections may be made as shown in Figure 8, the respective pipes being connected by a nipple 148 threaded in a bore 149 formed in the member 147. These connections will be equally spaced about the outside periphery of the member 147 as more particularly shown in Figure 1. Each annular groove is connected by a radial hole 150 to a longitudinally extending hole such as 151. These longitudinal holes terminate at the bottom of the member 147 into which the respective continuations of the various channels are threaded as more particularly shown at 152 in Figure 8. It will now be seen that the vertical standard 110 may be rotated relative to the base member 20 without disturbing the hydraulic connection in these various channels. The member 146 has an additional annular groove 153 to which fluid pressure is supplied from a pump 154 driven by a suitable prime mover, such as a motor 155 which may be either an electric motor or an internal combustion engine if the device is used in the field remote from a source of electrical energy. The annular groove 153 is connected by the pipe 48 to the passage 47 in the transmitter as shown in Figure 11 to supply the fluid pressure thereto.

Since the flexible hydraulic connection increases the possible leakage from the system, it is preferable to use the arrangement shown in Figures 4 and 5 which eliminates the use of this connection. In Figure 5 the transmitter 113 for the rotary movement of support 24 is carried by a bracket 156 which is integral with the base 20. The transmitter 137 is connected by a pair of spur gears 157 and 158 in a one to one ratio to a vertical shaft 159, this shaft being connected by bevel gears 160 in a one to one ratio to the horizontal shaft 161. This shaft has integrally secured thereto a bevel pinion 162 meshing with bevel gear 163 in a six to one ratio whereby one rotation of gear 163 will effect six revolutions in the gear 162. The gear 163 is keyed to one end of the pinion 23 which is fixed at the upper end of the support 21.

The transmitter 113 is connected by a spur gear train comprising gears 164, 165 and 166 in a one to one ratio to shaft 167. This shaft carries on its upper end a bevel pinion 168 meshing with the bevel gear 169 fixed to the support 24.

The transmitter 113 is connected by the hydraulic cable 170 having four individual lines inclosed therein to the receiver 124 in the same manner as before, the receiver in turn controls

the movement of the servomotor 126 in the same manner as before. The output shaft 127 of this servomotor is connected, however, by spur gear 171 to gear 172 in a three to one ratio the gear 172 having integral therewith a pinion 173 meshing with a gear 174 in a two to one ratio, the gear 174 being carried by the vertical shaft 175. By means of this gearing, one rotation of the shaft 127 will effect one-sixth of a revolution in the shaft 175. This shaft is connected by worm and worm wheel connection 176 to the support 15, the worm and worm wheel having a reduction ratio of one to six. The transmitter 137 is connected by the cable 176' to the receiver 142 which controls the operation of the servomotor 143 as in the construction shown in Figure 2, but the servomotor is connected by a spur gear 177 to a gear 178 secured to the end of shaft 179 in a one to six ratio whereby one rotation of gear 177 will effect one-sixth of a revolution in the shaft 179. This shaft is connected at the upper end by bevel gearing 180 in a one to one ratio to shaft 181. This shaft has fixed thereto a spiral gear 182 meshing with a spiral gear 183 in a one to six ratio, the latter gear being keyed to the end of the shaft 13 which is fixed with the gun support 11. An additional transmitter and receiver have been provided for the rotary movement of the vertical support 11 when rotated by means of the handle 31. This handle has a spring pressed grip 184 pivotally mounted thereon for frictionally engaging a flange 185 fixed with the support 28 for holding the standard 11 in any adjusted position. The lower end of the support 11 is therefore provided with a large spur gear 186 fixed for rotation therewith and meshing with the pinion gear 187 fixed to the end of the shaft 188 of the hydraulic transmitter 189. The ratio of this gearing is six to one whereby one rotation of the part 11 will effect six revolutions of the transmitter 189. This transmitter is connected by the cable 190 to the hydraulic receiver 191 which has the servomotor as in the previous constructions, the servomotor being connected to a worm 192 meshing with a worm wheel 193 in a 36 to one ratio, the worm wheel being carried by the lower end of the gun support 10.

The motive power unit includes an hydraulic motor more particularly shown in Figures 6 and 13 and the motor comprises a cylinder block 194 having a plurality of cylinders 195, 196, 197 and 198 formed therein. A piston such as 199 is reciprocably mounted in each cylinder and has a roller 200 antifrictionally journaled as by pin bearings 201 on a shaft 202. This shaft is flattened as at 203 on opposite sides of each end of the shaft for fitting into longitudinal grooves 204 formed in a depending skirt 205 of the piston. The upper end of each cylinder is provided with a port 206 and in order to obtain maximum guidance and minimum length of piston the opposite end of the piston from the roller is also provided with a skirt 207 having longitudinal slots 208 formed therein, one of the slots being opposite the port 206 to maintain communication between the port and the cylinder in all axial positions of the piston and the other slot receiving a pin 209 to prevent rotation of the piston in the cylinder and thereby maintaining the roller 200 in its proper plane relative to the control cam 210. This cam has three lobes 211, 212 and 213. These lobes are equally spaced and so arranged that it is acted upon successively by the pistons to cause rotation of the output shaft 127 of the motor. As shown in Fig-

ures 6 and 15, each port 206 is connected by a radial passage 214 to a port 215. The shaft 127 has a pair of longitudinal passages 216 and 217 formed therein which terminate in radial bores 218 and 219 which, as shown in Figure 6, lie in spaced planes. For instance, as shown in Figure 15, the passage 217 terminates in three radial bores 219, 220 and 221 lying in one plane and the passage 216 terminates in three radial passages 218, 222 and 223 lying in a different plane. It will also be observed from Figure 15 that these six radial passages are equally angularly positioned about the center of the shaft 127, even although they lie in different planes. Each radial passage, however, terminates in an arcuate slot as shown at 224 in Figure 6 whereby all of these radial passages are adapted to cooperate with all of the motor ports 215 in proper succession. For instance, if the channel 216 is connected to a source of pressure, the pressure will flow through radial passage 218 to piston 199 which, it will be noted, acts on the lobe 211 to cause counterclockwise rotation of the shaft 127 due to the fact that the point of contact 225 acts in offset relation to the center 226 of the shaft 127. When the channel 216 is under pressure the channel 217 is connected to exhaust and this permits the fluid acting on piston in cylinder 197 to exhaust and permit outward movement of the piston. As this rotation continues slightly beyond the position shown in Figures 13 and 16, the radial pressure channel 223 will be connected to supply pressure to cylinder 196 thereby causing inward movement of the contained piston and the radial exhaust passage 220 will be connected to cylinder 198 permitting the same to move outward. This sequence will continue, thereby causing continuous rotation of shaft 127 so long as pressure is supplied to channel 216 and channel 217 is connected to exhaust. If the connections are reversed to these two channels so that channel 217 is a pressure channel and 216 an exhaust channel, the direction of rotation of shaft 127 will be reversed. Further, if all flow is cut off from these two channels the motor will stop.

The flow to these two channels is controlled by a valve mechanism more particularly shown in Figures 6 and 12. As shown in Figure 6, the channel 216 is connected by a radial port 227 to an annular groove 228 formed in the valve housing 229 which is mounted for free rotation about the shaft 127. The channel 217 is connected by a radial port 230 to an annular groove 231 formed in the valve housing. The annular groove 228 is connected by the passage 232 to the annular groove 233 formed in the valve sleeve 234, this groove having radially extending passages 235 communicating with the interior of the valve sleeve. The annular groove 231 is connected by the passage 236 to the annular groove 237 formed in the valve sleeve and having radial ports 238 formed in the bottom thereof communicating with the interior of the sleeve. A valve plunger 239 is reciprocably mounted in the sleeve and has a spool 240 of sufficient width to close the pressure port 241 when in a central position, and a pair of end spools 242 and 243 which normally close the exhaust ports 244 and 245. Fluid pressure is delivered to the device through channel 246 which, as shown in Figure 16, communicates by radial passage 247 to the annular groove 248 formed in the sleeve 249. The sleeve 249 has a plurality of radial holes 250 formed in the bottom of groove 248 communi-

cating with an annular groove 251 formed in the periphery of shaft 127. A radial bore 252 in the bottom of this groove communicates with the longitudinal passages 253 formed in the shaft and terminating, as shown in Figure 12, in a similar radial passage 253 through which the fluid is supplied to the annular groove 254 formed in the valve housing 229 and connected with port 245. The two exhaust ports 244 and 245 are connected by passages 255 and 256 to the remaining annular groove 257 formed in the valve body which, in turn, is connected by radial passage 258 to the longitudinal bore 259. This bore communicates as shown in Figure 16, with a similar annular groove 260 to which the exhaust pipe 261 is connected. It will now be seen that fluid pressure is supplied to the pressure port 241 and this port is selectively connected to either passage 216 or 217 by the spool 248 carried by the valve plunger 239.

This valve plunger has a slot 262 formed in the end thereof for receiving a ball-ended bell crank 263 pivotally mounted at 264 in the valve housing 229. The other arm 265 of this bell crank has a bifurcated slot 266 in which fits a pin 267 carried by, as shown in Figure 14, a rotatable plate 268 fixed as shown in Figure 6, to the cam plate 46. It will now be apparent that as the cam plate 46 of the receiver member is rotated, it will act through the plate 268 and pins 269 to oscillate the bell crank 263 and move the valve plunger in a predetermined direction to connect the pressure port 241 to either passage 216 or 217 and thereby cause actuation of the motor which in turn will cause clockwise or counter-clockwise rotation of the output shaft 127.

After a predetermined rotation of the motor, it is apparent that the same must be stopped as it has effected rotation of the shaft 127 through a predetermined angular movement in accordance with the movement of the receiver member 46. There is therefore provided a feed back mechanism between the shaft 127 and the valve plunger 239 so as to centralize the spool 240 with respect to the pressure port 241. As previously mentioned, the motor operates in a six to one ratio with respect to the receiver and therefore the feed back mechanism must be of such construction as to permit six times the angular movement of receiver member 46 in the shaft 127 before terminating the movement thereof. To this end the shaft 127 is provided with a pinion gear 270 on the end thereof meshing with the spur gear 271 which is journaled on a shaft 272 carried by the valve housing 229 for movement therewith. The gear 271 meshes with an internal gear 273 which, as shown in Figure 6, is fixed with the outside housing of the motive power unit. This gearing is in such a ratio that as the shaft 271 rotates, it will cause the gear 271 to travel with respect to the fixed internal gear 273 and cause rotation of the valve housing 229 about the axis of shaft 127 and in a direction to follow up the movement of the valve plunger 239 caused by rotation of plate 268.

There has thus been provided an improved mechanism for transmitting motion from a movable object, such as the sighting element of a fire control system for anti-aircraft defense weapons, to the weapon itself, including pairs of interconnected hydraulic synchronous devices whereby movement of one causes a synchronized movement of the other, together with a power amplifying means consisting of a servo-motor con-

trolled by the receiver synchronous device, whereby the large torque necessary to move the gun will be produced by the servo-motor and only a small torque will be necessary to transmit the motion from the transmitter to the receiver.

What is claimed is:

1. In a signaling system, the combination of a rotatable transmitter, a remotely located rotatable receiver, a plurality of opposed pairs of fluid operable devices connected in couple formation to the receiver, a source of pressure fluid, means conducting the fluid for continuous flow to and from said devices, resistance means in the flow from said devices for controlling the individual pressures thereon, additional resistance means in the flow to said devices for varying the pressures as determined by the first-named resistances, means for rotating the receiver, means responsive to rotation of the transmitter for complementally varying one set of resistances and thereby inversely varying the pressures on the opposed devices to cause rotation of the receiver, and means responsive to receiver rotation for complementally varying the other set of resistances to equalize the opposed pressures on said devices.

2. In a signaling system, the combination of a rotatable transmitter, a remote rotatable receiver, a plurality of opposed pairs of fluid operable devices connected in couple formation to the receiver, a source of pressure operating fluid, a multiple channel connection for delivering fluid from said source to the individual devices, means in the individual channels for variably resisting the flow from said devices and thereby controlling the pressure thereon, additional means in the individual channels for variably resisting the flow to said devices, means for rotating the receiver, means responsive to rotation of the transmitter for varying the last-named resistances to vary the pressures acting on said devices and thereby cause rotation of the receiver, and means responsive to rotation of the receiver upon movement through an angle equal to the angle of rotation of the transmitter for equalizing the pressure on said devices to stop the receiver.

3. In a gun control mechanism, the combination of a transmitter having a rotatable portion, a sighting apparatus operatively connected to the rotatable portion of the transmitter for rotation thereof upon movement of the sighting apparatus through a given plane, a gun movable in a plane coincident with the plane of movement of the sighting apparatus, a receiver having a rotatable portion to move the gun, a servo-motor operatively connecting the receiver to the gun, a plurality of pairs of opposed fluid operable devices in the receiver, a source of pressure for delivering fluid continuously to said devices, means on the transmitter responsive to rotation of the rotatable portion of the transmitter for rotating the rotatable portion of the receiver, said means being responsive to rotation of the rotatable portion of the transmitter for inducing pressure changes in the fluid acting on said devices to cause rotation of the rotatable portion of the receiver, and means responsive to rotation of the rotatable portion of the receiver for equalizing said pressures when the receiver portion has moved through an angle equal to the movement of the transmitter portion.

4. In a signaling system, the combination of a rotatable transmitter, a remotely located rotatable receiver, a plurality of pairs of opposed fluid operable devices for connecting in couple formation to the receiver to rotate it, a source of pres-

sure operating fluid continuously flowing through said devices, means resisting the flow from said devices to create an operating pressure thereon, additional means for resisting the flow to said devices, said last-named means being located in the transmitter, means responsive to the rotation of the transmitter through a predetermined arc to effect a predetermined change in the opposing pressures in each couple, and means responsive to rotation of the movable receiver through the same predetermined arc to equalize the opposed pressures in each couple and to stop the receiver.

5. An hydraulic mechanism for maintaining a remotely located rotatable receiver element in synchronized relation with a rotatable transmitter element comprising a plurality of hydraulic channels, each channel containing a first resistance, a piston, and a second resistance in the order named, a common source of pressure for maintaining a continuous flow through all of said channels, said pistons being mounted in the receiver and arranged in couple formation, a multiple cam device arranged in contact with said pistons, the number of cams being odd in number with respect to the number of said pistons, each cam having a piston advancing portion and a piston retracting portion whereby an equal pressure on opposed pairs of pistons will tend to hold the cam device at rest, an increase in pressure on one piston over the other of a couple will cause rotation of the cam in a clockwise direction, an increase in pressure on the other piston will cause rotation in a counter-clockwise direction, and means in the transmitter for inducing pressure changes in the receiver to cause the receiver to move in synchronized relation with the transmitter.

6. In a system for transmitting motion between spaced points, the combination of a rotatable transmitter, a rotatable receiver, a plurality of hydraulic channels extending from the transmitter to the receiver, said receiver comprising four radial pistons arranged in opposing pairs, a rotatable cam member circumscribing the outer ends of said pistons and having a plurality of arcuate-shaped cam portions odd in number with respect to the numbers of said pistons, means connecting said channels to the inner end of said pistons to cause outward movement thereof into contact with said cam portions, independent exhaust channels connected to the respective pistons, resistance means in each channel variable in accordance with the position of the piston for creating variable pressures thereon, said transmitter element being similarly composed and including resistances for varying the pressure in said channels whereby rotation of the transmitter will cause an unbalancing of pressure in the respective pairs of channels to cause rotation of the receiver, which rotation will continue until the resistances in the receiver are made equal to the resistances in the transmitter.

7. In a mechanism for transmitting motion between spaced points, the combination of a rotatable transmitter, a rotatable follower, a plurality of channels extending from the transmitter to the follower, a source of pressure, means to couple the source of pressure to one end of all of said channels to maintain a continuous flow therethrough, movable pistons associated with

both ends of all of said channels and subject to the pressure therein, the pistons at one end being connected in pairs to the transmitter, the pistons at the other end being connected in pairs to the follower, one member of each pair opposing the direction of movement of the other member of said pair, whereby when equal hydraulic pressure exists in all of said channels said pistons will be in equilibrium, means for rotating the follower, means responsive to movement of the pistons at the transmitter upon rotation of the transmitter to differentially vary the quantity of flow in the several channels and thereby create differential pressures therein which will cause unbalance and resultant movement of the pistons at the follower and thus cause rotation of the follower, and means responsive to movement of the last-named pistons to re-establish equal pressures in said channels and thus terminate follower rotation.

8. Means for maintaining a rotatable follower in synchronized relation with a rotatable transmitter including a plurality of channels and extending from the transmitter to the follower, a source of pressure, means to couple the source of pressure to one end of all of said channels to maintain a continuous flow therethrough, movable pistons associated with both ends of all of said channels and subject to the pressure therein, the pistons at one end being connected in pairs to the transmitter, the pistons at the other end being connected in pairs to the follower, one member of each pair opposing the direction of movement of the other member of said pair, whereby when equal hydraulic pressure exists in all of said channels said pistons will be in equilibrium, and means for rotating the follower the last-named means being responsive to movement of the pistons at the transmitter upon rotation of the transmitter to differentially vary the quantity of flow in the several channels and thereby create differential pressures therein which will cause unbalance and resultant movement of the pistons at the follower and thus cause rotation of the follower, means responsive to movement of the last-named pistons to re-establish equal pressures in said channels and thus terminate follower rotation, and a servo-motor mechanism operable by the follower for amplifying the output torque thereof.
